HEATER HOUSING FOR HAIR CURLERS

John L. Benty, Scotch Plains, N.J., and Svend Fischlein,
Albertslund, Denmark, assignors to Bristol-Myers Com-
pany, New York, N.Y.

Filed Mar. 9, 1970, Ser. No. 21,794

Claims priority, application Denmark Oct. 7, 1969

Term of patent 14 years

Int. Cl. D28—03

U.S. Cl. D86—10

Fig. 1.

Fig. 4.

Fig. 2.

FIG. 1 is a front perspective view of a heater housing for hair curlers showing our new design;

FIG. 2 is a perspective view thereof in open position;

FIG. 3 is a front elevational view of the heater housing for hair curlers in closed position;

FIG. 4 is a top plan view thereof;

FIG. 5 is a side elevational view;

FIG. 6 is a side elevational view of the side opposite thereto; and

FIG. 7 is a bottom plan view.

We claim:

The ornamental design for a heater housing for hair curlers, substantially as shown.
